UNITED STATES PATENT OFFICE.

JAMES H. RAND, OF NEWTON, MASSACHUSETTS.

INDEX MEMBER.

1,248,712.

Specification of Letters Patent. Patented Dec. 4, 1917.

Application filed January 2, 1917. Serial No. 140,032.

To all whom it may concern:

Be it known that I, JAMES H. RAND, a citizen of the United States, and resident of Newton, in the county of Middlesex and 5 State of Massachusetts, have invented new and useful Improvements in Index Members, of which the following is a specification.

This invention relates to card index members for so-called visible indexes of the type in which a series of overlapping cards are supported in a frame by means of supporting bars or carriers, the ends of which are inserted in opposed guide channels of the frame. 10 The cards are attached at one edge to the bars or carriers while the opposite edges are free, so that the cards may be swung on their bars or carriers to permit the inspection or making of entries on underlying cards, 15 while in normal position the cards overlap one another with their free margins exposed to display indexing matter. The present invention consists chiefly in certain novel features of construction by which a set of plain 20 index cards such as are usually held in a tray or drawer, may be readily converted into an overlapping card index of the visible index type. The advantages of this type 25 of index over the old fashioned card index consisting of a stack of cards in a tray have long been understood, but the labor and expense of copying the entries from an old 30 card index system into an overlapping card, visible index, together with the likelihood 35 of error, have stood in the way of changing from the old system to the new. The principal object of the present invention is to provide means by which an old style card index, with all its valuable entries may be 40 made over into an overlapping card visible index.

In the accompanying drawings which illustrate the invention,—

Figure 1 is a front face view of the card 45 index member;

Fig. 2 is an enlarged section on line 2—2 of Fig. 1;

Fig. 3 is a rear face view of the card;

Fig. 4 is a plan view of the fabric strip 50 hereinafter described;

Fig. 5 is a perspective view of part of one of the sheaths; and Fig. 6 is a sectional view similar to the lower part of Fig. 2 illustrating a modification.

55 The card proper, which forms the body of the card index member is shown at A.

B is a strip of flexible sheet material preferably textile fabric, folded over on itself on a line b. One of the folds b² is wider than the other fold b', and may be cut away 60 if desired to form a plurality of attaching tabs b³. The fabric strip B is preferably sized or otherwise stiffened sufficiently to enable the fold b' to support the weight of the card when the parts are assembled as 65 hereinafter described, and may also be coated with an adhesive gum, on such parts at least as overlie the card A, for the ready attachment of the strip to the card.

C is a sheath of sheet celluloid, or other 70 resilient transparent sheet material, having longitudinal marginal lips c and c' bent toward each other to form a substantially tubular structure, in which the folded strip B is inserted endwise, with one fold b' wholly 75 contained within the sheath and supported by lip c', while the other fold projects outside of the sheath between the lips.

The card A is attached at its upper edge to the outwardly projecting part of the fabric strip, and is wholly outside of the sheath and spaced a little therefrom, so as to leave a narrow area of the fabric uncovered to form a flexible hinge. It will be understood 80 that the upper sheath C constitutes a resilient supporting bar or carrier, whose laterally extending ends are mounted in the usual guide flanges of the frame.

The structure at the lower edge of the card is precisely similar, save that as the sheath 90 here is merely a protective sheath and holder for an index slip, the card body A may extend completely into the sheath between the lips thereof, thus affording a comparatively rigid connection instead of a hinged connection between the sheath and the card.

An indicator slip or insert D is removably held within the lower sheath C, in front of the fabric fold b'; and the fold b' instead of being an attached strip might be formed 100 by bending or folding the margin of the card itself over upon the body of the card as shown at a Fig. 6, in which case the indicator strip D could be inserted in front of the folded marginal member a, between it 105 and the face of the sheath C in a position corresponding to that shown in Fig. 2.

The use of the thin fabric strip for the attaching fold results in a very thin, flat structure and makes it possible to use a 110 very thin, flat sheath, thus avoiding undue bulkiness in the assembled index. It is to be

understood that the thickness of the parts shown in Fig. 2 is greatly exaggerated for the sake of clearness. Furthermore, the use of a separate attaching strip makes it possible to use an ordinary old style card index, without recopying, by merely sticking or otherwise attaching the cards to the flexible fabric strip B, folding the latter and inserting the fold in the sheath C. The sheath 10 may then be mounted in a visible index frame in the usual manner. The protective sheath and the removable indicator slip at the bottom or free edge of the card are similarly attached by a fabric strip B, and 15 a complete overlapping card visible index system, with removable supporting bars or sheaths and removable indicator slips, is produced without sacrificing the old card system.

20 I claim:

1. A card index member comprising a body of sheet material, a separate strip of flexible sheet material attached to the edge of the body and folded over on itself, and 25 a sheath engaging and inclosing the folded over part of the strip attached to the body.
2. A card index member comprising a body of sheet material, a separate strip of textile fabric attached to the edge of the 30 body and folded over on itself, and a sheath engaging and inclosing the folded over part of the fabric strip attached to the body.
3. A card index member comprising a sheath having longitudinal marginal lips 35 bent toward each other to form a tubular structure, a strip of flexible sheet material folded over on itself, one fold being wholly contained within the sheath and the other projecting out of the sheath between said 40 lips, and a body of sheet material attached to the part of the flexible strip projecting outside of the sheath.

4. A card index member comprising a sheath having longitudinal marginal lips bent toward each other to form a tubular 45 structure, a strip of stiffened textile fabric folded over on itself, one fold being wholly contained within the sheath and the other projecting out of the sheath between said lips, and a body of sheet material attached 50 to the part of the fabric strip projecting outside of the sheath.

5. A card index member comprising a sheath having longitudinal marginal lips bent toward each other to form a tubular 55 structure, a strip of stiffened textile fabric folded over on itself, one fold being wholly contained within the sheath and the other projecting out of the sheath between said lips, and a card, wholly outside of the sheath 60 and spaced therefrom, attached to the part of the fabric strip projecting outside of the sheath, the fabric between the card and the sheath constituting a flexible hinge.

6. A card index member comprising a 65 body of sheet material, having at its edge a marginal member folded over upon the body of the card, a sheath having longitudinal retaining lips engaging and inclosing said folded marginal member, and a removable indicator slip between the folded marginal member and the face of the sheath.

7. A card index member comprising a body of sheet material, a folded marginal member separately formed of textile fabric 75 at the edge of the body, a sheath having longitudinal retaining lips engaging and inclosing said folded marginal member, and a removable indicator slip between the folded 80 marginal member, and the face of the sheath.

Signed by me at Boston, Massachusetts,
this 28th day of December, 1916.

JAMES H. RAND.
